UNITED STATES PATENT OFFICE.

ANDREW J. COMPTON, OF TRENTON, NEW JERSEY.

ADJUSTABLE PAINT-BRUSH HOLDER.

No. 918,420.

Specification of Letters Patent.

Patented April 13, 1909.

Application filed March 25, 1908. Serial No. 423,243.

To all whom it may concern:

Be it known that I, ANDREW J. COMPTON, a citizen of the United States, residing at Trenton, in the county of Mercer and State 5 of New Jersey, have invented new and useful Improvements in Adjustable Paint-Brush Holders, of which the following is a specification.

This invention relates to adjustable paint 10 brush holder, and the object of the invention is to provide a device of this character whereby the handle of a brush may be readily extended so that the operator may conveniently paint portions of a building or 15 the like not readily accessible with the ordinary short handled brushes.

With these objects in view the invention resides in the novel construction and arrangement of elements, hereinafter fully described 20 and claimed.

In the accompanying drawings, Figure 1 is a side elevation of a paint brush provided with my extension device. Fig. 2 is a top plan view of the same. Fig. 3 is a trans- 25 verse sectional view through one of the sockets. Fig. 4 is a side elevation of the device applied to an ordinary flat brush. Fig. 5 is a front elevation of the same.

In the accompanying drawings, and referring 30 particularly to Figs. 1 and 2 thereof the numeral 1 designates the handle of an ordinary brush. This handle 1 is adapted to be received within the brush holding socket 2 of my improvement. This socket 2 is pro- 35 vided upon one of its ends, and adjacent its bore with an ear 3, having a central perforation adapted for the reception of a threaded bolt 4, provided by a similar ear 5 secured upon the handle holding socket 6. The sockets 2 40 and 6 may be constructed of any desired or preferred material, and the socket 6 is pro- 45 vided with a closed head 7 adapted to prevent the operating handle 8 from extending through the bore of the socket. The sockets 2 and 6 are also provided with threaded 50 openings adapted for the reception of retaining elements 9 and 10, by which the brush and operating handle is secured upon the sockets. By providing the ears 3 and 5 of the socket members offset from the body of 55 the sockets, it will be seen that the socket 2 may be adjusted at any desired angle in relation to the socket 6, and that the handle of the brush 1 may project beyond the socket

without contracting with or interfering with 55 the ear 5 of the socket 6. If desired the meeting faces of the ears 3 and 5 may be provided with teeth, as illustrated in the drawings. When the sockets are not in use for extending a brush, it will be readily seen 60 that they will be folded upon each other and conveniently carried within the pocket of an operator.

In Figs. 4 and 5 I have shown a method 65 securing a flat brush to the operating handle socket 6. In these views I have provided a member 11 having an ear 12 adapted to engage the ear 5 of the socket 6, and to be retained in any desired position thereon by the threaded element 13, engaging a projection 70 14 provided by the ear 12. The member 11 is also provided with a threaded extension 15 at a substantial right angle to the member 14. This threaded member 15 is adapt- 75 ed to be positioned within a suitable perforation provided upon the brush 16, and to be retained thereon by a winged nut 17. The member 11 is also provided with teeth 18, adapted to engage the opposite face of the head of the brush 16 to that engaged by 80 the winged nut 17. The face of the ear 12 may be corrugated as shown, and the element 11 may be retained as a permanent fixture upon the brush 16 should it be desired. 85

Having thus fully described the invention what is claimed as new is:

In a device of the character described, a socket having means whereby a handle is secured therein, said socket being provided 90 with a head and having an ear on one side offset from the body of and extending in a direction parallel to the longitudinal axis of the socket, and a brush holding socket being provided with means whereby a brush handle is retained therein and being provided with an ear on one side offset from the body of and extending in a direction parallel to the longitudinal axis of the socket, and means whereby the ears are retained in a 100 desired position upon each other.

In testimony whereof I affix my signature in presence of two witnesses.

ANDREW J. COMPTON.
